UNITED STATES PATENT OFFICE.

FRANCIS T. MURRAY, OF CHICAGO, ILLINOIS.

DESIGN FOR A CLOTHESLINE-HOLDER.

59,427.

Specification for Design.

Patented Oct. 18, 1921.

Application filed November 20, 1920. Serial No. 425,572. Term of patent 7 years.

To all whom it may concern:

Be it known that I, FRANCIS T. MURRAY, new ornamental design for a clothesline a citizen of the United States, residing at holder; Chicago, in the county of Cook and State of Illinois, have invented a new, original, and ornamental Design for a Clothesline-Holder, of which the following is a specification, reference being had to the accompanying drawing, forming part thereof.

Fig. 2 illustrates a side elevation of same.

I claim:

The ornamental design for a clothesline holder as shown.

FRANCIS T. MURRAY.
